UNITED STATES PATENT OFFICE.

ROBERT B. HOUSLEY, OF LAS VEGAS, NEVADA.

FLUE CONNECTION FOR FIRE-SHEETS.

1,080,009.

Specification of Letters Patent.

Patented Dec. 2, 1913.

Application filed July 27, 1911, Serial No. 640,926. Renewed October 27, 1913. Serial No. 797,648.

To all whom it may concern:

Be it known that I, ROBERT B. HOUSLEY, a citizen of the United States, residing at Las Vegas, in the county of Clark and State 5 of Nevada, have invented a new and useful Flue Connection for Fire-Sheets, of which the following is a specification.

This invention relates to an improved method of securing flues to fire sheets, and 10 the objects of the invention are to positively prevent leakage and avoid the operation of expanding the flues.

The accompanying drawings illustrate the invention and referring thereto, Figure 1 is 15 a perspective view in section. Fig. 2 is a cross section on line x^2-x^2 Fig. 1. Fig. 3 is a side elevation of the bushing, partly in section. Fig. 4 is a vertical section showing a modified form of the invention.

20 1 designates the fire sheet formed with a perforation 2 and having a deep, annular groove on one side lying close to and concentric with the orifice 2. The inner wall of the groove is smooth, its lower wall is 25 smooth and its outer wall is threaded, as at 3. Within the annular groove is a bushing 4, shown in detail in Fig. 3, which is preferably constructed of copper and at its lower end has a flange 5 which rests flatly 30 against the bottom wall of the annular groove referred to, the outer portion of the flange lying in an enlarged space 5^a formed in the annular groove at the end of the flue 7. The formation of the said annular 35 groove leaves a circular ring portion 6, which ring portion is surrounded by the bushing 4, the smooth inner walls of the bushing 4 closely fitting the smooth, outer wall of the ring 6. The flue 7 has a threaded 40 end 8 which is screwed into the threads 3, the inner end of the flue 7 tightly abutting the flange 5 of the bushing 4 and the inner smooth wall of the flue 7 closely fitting the outer wall of the bushing 4, so that when 45 the flue 7 is screwed tightly into place the metal of the bushing 4 is, owing to its rela-

tive malleability, forced into intimate contact with the adjacent wall of the groove at all points and thus acts as a gasket to positively and permanently seal the joint 50 between the flue and fire sheet and thus absolutely prevent leakage.

Instead of screwing the flue directly into the sheet, said flue may be connected to the bushing as indicated in Fig. 4 by a coupling 55 or collar 9 and nipple 7', the nipple 7' screwing into the sheet, the collar 9 screwing onto the nipple and the flue 7 screwing into the collar, the construction being otherwise as above described. In this case, the nipple 7' 60 and collar 9 form an extension of the flue and in fact, constitute a part of the flue as far as the operation is concerned, and when the term "flue" is herein used, it covers any extension thereof such as the nipple and collar described. 65

What I claim is:

A fire sheet having a perforation and provided with an annular groove around the perforation, the outer wall of said groove 70 being threaded, a flue having external threads fitting the threads of the outer wall and forming a longitudinal space in the annular groove along the flue and an enlarged space at the end of the flue, a bushing with 75 its inner face bearing against the inner wall of said annular groove and its outer face bearing against the inner face of the flue thereby filling said longitudinal space, said bushing having an outwardly directed flange 80 which completely fills the said enlarged space between the end of the flue, and the outer, inner, and bottom walls of said groove. 85

In testimony whereof, I have hereunto set 85 my hand at Las Vegas, Nevada, this 26th day of May, 1911.

ROBERT B. HOUSLEY.
